UNITED STATES PATENT OFFICE.

JOHN MARTINO AND JOHN CURRIE, OF PHILADELPHIA, PENNSYLVANIA.

DESIGN FOR A PARLOR-STOVE.

Specification forming part of Design No. 5,547, dated February 20, 1872.

Specification describing a Design for Parlor-Stoves, invented by JOHN MARTINO and JOHN CURRIE, of the city of Philadelphia and State of Pennsylvania.

The nature of our design is fully represented in the accompanying photographic illustrations, to which reference is made.

The base-plate A has an annular swell, *a*, and cove, *b*, the former of which has ornaments, *c*. The two front sliding register-doors B and side plates C, over which they slide, are of the same height. The doors have, around the register D, a leaf and scroll ornament, *d*. The side plates C have X-shaped ornaments *d'*, alternating with diamond-shaped ornaments in connection. They have a bead ornament around their lower edge. The cap-ring E is of ogee form at top, with a double round beneath it. The latter has ornaments *e'*, similar to ornaments *c* of the base-plate. The ogee has leaves *e*, with their points running upward. The screen around the fire-cylinder is formed of a number of plates, F, having each an ornament springing from an oval, which is pierced through for the passage of air to protect the cylinder; the cap-ring G, of somewhat ogee form at top, with a round at bottom, terminating with a scallop edge, from which spring ornaments *g*, with small dots between them. Upon the ring G rest a series of plates, H, which have vines *h* running from the top to the center downward, and from the bottom to the center upward. On these plates are hung mica door-frames I, which have in their center a tie-shaped ornament, *j*, having a double leaf at top and a single leaf at its bottom. Around the frame is a twisted ornament, *J*, having oval centers. Resting on the plates H is the ring K, which has a double round, the lower one having a scalloped edge and an ornamentation like the ring G. The upper cast-iron body is made up

of a number of staves, L, having at their upper and lower edges oval ornaments *k*, above and below from which springs a vine, *l*, around the staves. In the center of the staves is a claw ornament, M, with an oval center and a spear-head at top and bottom. There is a cap-ring, N, which rests on these staves, of ogee shape, which has a series of tulip-shaped ornaments, having at the bottom a double scroll. On this ring rests the top plate O, made up of a series of moldings, the center one being round and the bottom and top ogee. The round has an X ornamentation similar to that of the plate C. The bottom ogee has a scalloped edge, around which is a running ornament, *m*. Around the upper ogee lies a little frilled ornament, *n*. The cover P, which rests on the top plate O, is made up of a series of moldings, the lower one being a swell, the second of ogee form, the third a bevel, and the fourth a cove. Around the edge of the lower molding is an egg-shaped ornament, O. The ogee has a ruffle ornament, with the points running downward. The cove has a running ornament, *p*. Upon this cover rests the urn Q, which has pendent ornaments *q*. The cover of the urn has an ornament around its edge somewhat similar to that around the edge of the cover P. The cover is pierced through for the passage of vapor from the bowl of the urn. The top of the cover has a rosette ornament, *r*. The cover has a vertical ornamental handle, R.

We claim as our invention—

The design for a parlor-stove, as shown and described.

JOHN MARTINO.
JOHN CURRIE.
